UNITED STATES PATENT OFFICE.

ARTHUR EHLERT, OF WOLLIN, WOLLIN ISLAND, GERMANY.

IGNITING DEVICE.

1,027,600.

Specification of Letters Patent. Patented May 28, 1912.

Application filed August 10, 1911. Serial No. 643,320.

To all whom it may concern:

Be it known that I, ARTHUR EHLERT, a subject of the Emperor of Germany, residing at 16 Mittelstrasse, Wollin, Wollin Island, Germany, barrister, (whose post-office address is 16. Mittelstrasse, Wollin, Wollin Island, Germany,) have invented certain new and useful Improvements in Igniting Devices, of which the following is 10 a specification.

This invention relates to igniting devices of the kind operated by means of a pyrophorous metal for example cerium-iron or the like. Such an igniting device forms in 15 combination with a receptacle for a combustible fluid, benzine for example, an igniter which can be constructed in any desired manner and be placed on a wall, on a table or carried in the pocket.

20 The igniting device consists of a staff-like body, which when not in use is kept in the igniter-holder or receptacle, being immersed in the liquid contents thereof. In order to produce a flame the igniting device is taken 25 out of its holder, and the effective end of it is drawn over a file or friction surface arranged on the holder, whereby sparks are produced which ignite a wick.

As compared with such devices as heretofore made, the new igniting device which 30 forms the subject of the present invention has the important advantages: (1) That in consequence of the arrangement of the wick, which is surrounded by the pyrophorous 35 metal, ignition must always be reliably effected; (2) it is not necessary that the striking should be effected in any particular direction and the igniting device can be held in any manner as desired; (3) the file is not 40 moistened and a failure to act cannot arise from this cause; and (4) when the striking is effected the wick is not cut up on the file as hitherto.

The wick, as well as the pyrophorous 45 metal can be easily regulated with regard to the length projecting from the staff-like body; and, when worn out, new parts can be readily substituted.

The invention is illustrated in the accompanying drawing.

Figure 1 is an elevation, the igniter-holder or receptacle being shown partially in section; Fig. 2 represents the igniting-device in section; Fig. 3 is an inverted plan of

same. Figs. 4 and 5 illustrate another form, 55 the effective part being shown in inverted plan. Figs. 6 and 7 are similar views illustrating a further modification; Figs. 8 and 9 represent pieces of pyrophorous metal in combination with brass casings, which are 60 intended to be fixed on the igniting device by means of screw-threads.

In the form shown in Figs. 1 to 3 the igniting device consists of a tubular casing *a*, provided at the top with an extension *b* 65 that is screw-threaded or of conical form and which serves for effecting the fixing of the tube in the igniter-holder *c*. The extension piece *b* is preferably provided with a handle *d*. On the lower end of the tube *a* 70 is a screw-socket *f* which is intended, in a manner similar to that in a pencil-case, to hold a piece of pyrophorous metal or the like *g*, the length to which this extends from the socket *f* being capable of regulation. 75 The piece of pyrophorous metal *g* is of tubular form and in the boring thereof is a wick *h* which extends, or is compressed into the interior of the tube *a*, so that it can absorb and retain a quantity of the liquid 80 contained in the igniter-holder *c*. On the igniter-holder *c* a friction-surface or file *i* is provided.

When the wick *h* has become saturated with the combustible liquid, the igniting device is taken out of the igniter-holder *c* and the piece of pyrophorous metal *g* is struck upon the file *i*. Thereby sparks are produced which ignite the wick. This will burn for some time, so that the flame may be used 90 for igniting burners, lamps, cigars, etc., as well as for illuminating purposes.

The essential novelty of the described igniting-device is that the wick to be ignited is surrounded by the pyrophorous metal. 95 The advantages obtained thereby are set out in the introduction.

In the form of the invention illustrated in Figs. 1, 2 and 3 the piece of pyrophorous metal is constructed in tubular form. In the 100 forms shown in Figs. 4 and 5, and in Figs. 6 and 7 of the drawings, thin solid metal bodies *g* in the form of pins are used and these are so arranged that the wick *h* lies between two, three or more of such pins. 105 These pins *g* and the wick *h* are fixed in sockets *f*, which are constructed for example as clamping or screw-sockets. In these

forms of the invention the fundamental idea of the invention, that of surrounding the wick with pyrophorous metal, is preserved.

As shown in Figs. 8 and 9 the pieces of pyrophorous metal *g* may be fixed in metal tubes *k* or on brass-tubes. When the striking is effected with this form the metal tubes *k* are worn by contact with the file *i*. The tubes *k* may be fixed to the tube *a* by means of screw-threads and in combination with their pieces of metal *g* form the supplementary renewable parts of the device.

Having fully described my invention, what I claim and desire to secure by Letters Patent is:—

1. A pyrophorous igniting device comprising a body of pyrophorous material and a wick within said body.
2. A pyrophorous igniting device comprising a tube of pyrophorous material closed at one end and a wick within said tube and projecting partly through the open end of said tube.
3. A pyrophorous igniting device comprising a body of pyrophorous material, a wick within said body, an adjustable clamp-

ing socket for said body, and an igniter holder having means whereby said socket can be adjustably clamped thereto.

4. A pyrophorous igniting device comprising a body of pyrophorous material, a wick within said body, a tube to which said body is fixed, and means for securing said tube to the casing of the igniter holder, substantially as described and for the purpose 35 stated.

5. A pyrophorous igniting device comprising a body of pyrophorous material, a wick within said body, a tube to which said body is fixed, and means for securing said tube to the casing of the igniter holder, an adjustable clamping socket for said body, and an igniter holder having means whereby said socket can be adjustably clamped thereto, substantially as described. 40 45

In testimony whereof I have hereunto set my hand in presence of two subscribing witnesses this 26th day of July 1911.

ARTHUR EHLERT.
